UNITED STATES PATENT OFFICE.

GEORGE SPENCEE NEELEY, OF ST. LOUIS COUNTY, MISSOURI, ASSIGNEE OF ONE-HALF
TO THOMAS O. MOLONEY, OF ST. LOUIS, MISSOURI.

FUSE-SUPPORT.

1,236,001.

Specification of Letters Patent. Patented Aug. 7, 1917.

Application filed May 22, 1916. Serial No. 98,174.

To all whom it may concern:

Be it known that I, GEORGE SPENCER NEELEY, a citizen of the United States, residing at the county of St. Louis, State of

5 Missouri, have invented a certain new and useful Improvement in Fuse-Supports, of which the following is a full, clear, and exact description, such as will enable others skilled in the art to which it appertains to 10 make and use the same, reference being had to the accompanying drawings, forming part of this specification.

This invention relates broadly to electrical distribution, and more specifically to 15 a form of support for fuse or cut-out boxes, and lines in association therewith, in high tension distribution systems.

As is well known in the art, it is customary to transmit current on distribution 20 lines under a high pressure, and at points where it is desired to take off current for use, to step down the high potential current to the proper voltage by a transformer, which is customarily supported on the pole 25 which carries the primary lines. As a means for protecting the transformer and the secondary circuit from high voltages and overload it is customary to insert a fuse or cut-out in the lead from the high voltage 30 line to the transformer. Due to various causes, these fuses are frequently blown out, and of course, require renewal. The operation of renewing fuses is attended with considerable risk because of the proximity of 35 the fuse box to conductors carrying high voltage, and this is particularly true during rain, or when the pole or cross arms are wet or incrusted with ice.

It is the particular object of my invention 40 to provide an arrangement for supporting the fuse box relative to the cross arm and the high potential line in such fashion as to afford maximum insulation of the parts which must be handled in renewing 45 the fuse, from the pole and from the charged conductors. It is my object also to provide such an arrangement which is adapted for the utilization of the forms of fuse boxes, insulators, etc., which are now approved 50 practice and commonly employed, and to

provide clearance space on the cross arm for mounting the usual lightning arrester installation for the further protection of the transformer.

Other objects of my invention will be 55 obvious or pointed out hereinafter.

In the drawings—

Figure 1 is a front elevation of the upper portion of a line pole showing the application of my invention. 60

Fig. 2 is a detail showing a side elevation of my invention as utilized at a dead end of a primary line.

Fig. 3 is a side elevation showing my invention as employed at a point where the 65 primary line is continued; and

Fig. 4 is a detail illustrating the bracket forming a portion of my invention, and its application.

In said drawings, let the numeral 1 indicate a conventional line supporting pole upon which is carried a primary cross arm 2 and a secondary cross arm 4. A transformer 5 is supported on the pole in any suitable fashion. It will be understood that 70 this assembly represents a condition obtaining at a point where it is desired to take current from the primary or high tension distribution lines for use. Let the numeral 6 indicate an insulator pin of conventional 75 form, which is supported on the cross arm 2 in customary fashion. An insulator 7 of approved design is mounted on the pin 6 in the usual manner. Customarily such an insulator so mounted is used to carry the 80 transmission line. At a point where it is desired to insert a fuse or cut-out box, however, the transmission line is not supported on this insulator, but is supported in a manner hereinafter to be described. 85

Let the numeral 8 represent a fuse box or cut-out of conventional type, the same including a skirt portion 8^a which forms an enclosure and protection for the fuse plug 8^b. The latter is insertible into the skirt portion 95 8^a from below, and in such fashion that a fuse carried on the entering portion of fuse plug 8^b will be received within the skirt portion 8^a and protected thereby from the elements. The fuse box has a pair of longitu- 100

dinally extending apertures adapted for the reception of supporting means. In connection with the fuse box, I employ a form of bracket 9 which is attached to the former by means of the bolts 10 passing through the longitudinal apertures of the box, and seated in ears 9^a of the bracket. The bracket is in two pieces which may be identical, each including in addition to the ear 9^a, an arm 9^b extending from said ear and to a clamping portion 9^c. The clamping portion 9^c is semi-annular in form, and adjacent its extremities are formed transversely extending sleeves 9^d. The clamping portion 9^c, arm 9^b, ear 9^a, and sleeves 9^d are preferably formed integral, as a casting of bronze or high quality iron such as will be free from oxidization by the weather. The size and contour of the clamping portion 9^c is such that when two of the bracket portions are placed together in the relationship illustrated in Fig. 4, the clamping portions will form an annulus adapted to encircle and operably engage the neck of an insulator 7. The bracket is secured on such an insulator by means of bolts 11 which are seated in the sleeve portions 9^d. When so clamped to an insulator 7, and with the fuse box supported on the ears 9^a by means of the bolts 10, the box will be supported from the insulator, and spaced apart therefrom, and spaced entirely apart from the cross arm 2. This will place the fuse plug 8^b in an isolated position an appreciable distance apart from the cross arm. In case the support is installed at the terminus or dead end of the primary line, I will employ as one of the members comprising the bracket, a member having a ring 12 formed on its extremity opposite the ear portion 9^a. To this ring will be attached a short suspension member 14 carrying an insulator 15 at its extremity. The high tension line wire 16 will be tied to the insulator 15, and a lead from the line wire will be taken in the form of a choke coil 16, to one of the fuse connections on the fuse box 8. Another wire 17 will connect the other fuse connection on the box 8 with the primary tap of the transformer. By virtue of this arrangement, it will be seen that the fuse plug 8^b is very conveniently located with respect to the high tension line as regards the possibility of its being manipulated without subjecting the operator to the danger of coming into contact with the high tension line. The high tension line is insulated completely from the cross arm both by the insulator 14 and the insulator 7. Likewise, the fuse plug 8^b is completely insulated from the cross arm by the insulator 7 and by its position entirely apart therefrom.

In Fig. 3, I have illustrated the applica-

tion of my invention at a point other than at a dead end of the primary line. In this position, the fuse box is supported from the insulator 7 as just described, but the transmission line 16 instead of being secured to an eye of the bracket, is tied to the fuse box, the lead and choke coil 16 being brought down from the transmission line to the contact on the box. 65

By virtue of this construction, it will be observed, not only is the fuse plug supported a substantial distance apart from the cross arm, but the leads to the box, and from the box to the transformer are all supported a substantial distance apart from the pole and the cross arms. By virtue of this arrangement, this form of support provides an effective protection for the pole and for a lineman manipulating the fuse plug, as the disposal of the fuse box in a position spaced apart horizontally from the arm prevents short-circuiting from the box to the arm in the case of rain. 70 75 80 85

I am aware that the construction and arrangement above described is adapted to variations and modifications without departing from the scope of the invention indicated in the following claims. 90

What I claim is:

1. In a transmission system, a support for electrical conductors including a supporting arm, an insulator supported thereon, a bracket supported on the insulator and extending to one side of the arm, and a fuse box supported on the bracket with its terminals at one side of and apart from the arm, said fuse box being arranged for connection with a transmission line to support the same away from the bracket and arm 100 95

2. In a pole-supported transmission system, the combination of a supporting arm, an insulator supported thereon, a bracket supported on the insulator and extending laterally thereof clear of the arm, a fuse box supported by the bracket and spaced apart from the arm, a plug supported in the fuse box and having an external manipulative portion spaced apart horizontally from the arm, and said fuse box being arranged for electrical connection with a transmission line and to support said transmission line out of electrical connection with the bracket and supporting arm. 115

3. In a pole-supported transmission system, the combination of a supporting arm, an insulator supported upon and vertically above the arm, a bracket supported on said insulator and extending laterally from the arm, a fuse box supported by said bracket in a position spaced apart horizontally from the arm, a transmission line supported by said fuse box out of electrical connection with the bracket and the arm, and a removable

able fuse plug supported in the fuse box and including a fuse having electrical connection with said transmission line and an external manipulative portion spaced apart 5 from the transmission line and from the arm.

In testimony whereof I hereunto affix my

signature in the presence of two witnesses, this 19th day of May, 1916.

GEORGE SPENCER NEELEY.
